UNITED STATES PATENT OFFICE.

ROBERT A. FORESMAN, OF MOORE, PENNSYLVANIA, ASSIGNOR TO WESTINGHOUSE ELECTRIC & MANUFACTURING COMPANY, A CORPORATION OF PENNSYLVANIA.

FURNACE WALL.

Application filed May 18, 1926. Serial No. 109,998.

My invention relates to high temperature furnaces, more particularly to boiler furnaces, and has for an object to provide apparatus of the character designated with a wall 5 which shall be so constructed as to withstand high furnace temperatures without rapid deterioration.

A more specific object of my invention is to provide a water cooled furnace wall embodying interchangeable wall elements which 10 may be quickly installed and readily replaced.

A still further object of my invention is to provide a furnace wall capable of withstanding high furnace temperatures and which, in association with an outer wall, effectively prevents excessive radiation of 15 heat from the furnace to the boiler room.

Apparatus embodying features of my invention is illustrated in the accompanying drawings, forming a part of this application, in which:

Fig. 1 is a fragmentary sectional view of a furnace wall made in accordance with my 25 invention and taken along the line I—I of Fig. 2;

Fig. 2 is a view in elevation of the structure shown in Fig. 1 and viewed from the outside of the furnace;

Fig. 3 is a horizontal sectional view taken 30 along the line III—III of Fig. 2;

Fig. 4 is a view showing the removal of a wall element similar to that illustrated in Fig. 3 from the outside of the furnace;

Fig. 5 is a horizontal sectional view taken 35 along the line V—V of Fig. 2;

Fig. 6 is a view in elevation of the structure shown in Fig. 5 when seen from the inside of the furnace;

And Fig. 7 is a sectional plan view showing a preferred method of installing my improved furnace wall in association with an outer wall, to prevent excessive heat radiation from the furnace.

In my application, Serial No. 718,942, filed December 23, 1924, and my application, Serial No. 32,111, filed May 22, 1925, both assigned to the Westinghouse Electric and Manufacturing Company, there is disclosed

a furnace wall of the general character covered by this application. The improvement herein disclosed consists in providing wall elements which may be readily installed and replaced, which permit of relative expansion and contraction between the wall ele-

ments and their associated parts, and which permit of the greatest possible transfer of heat between the furnace and the water cooled tubes of the wall.

Briefly, the invention consists in a furnace 60 wall comprising a plurality of spaced, aligned tubes together with wall elements each having a hook-like part extending part way around an associated tube for supporting the element in its relation to the tubes, 65 together with means for joining the elements together to prevent an undesired disengagement from the tubes, said joining means providing ready assembly and disassembly under all conditions of service.

The wall elements, in general, take two distinct forms, one of which is particularly adapted for association with the furnace wall where it comes in contact with the fuel bed and the other of which is particularly adapted for application above the line of the fuel bed. The assembled wall may be associated with an outer wall so situated as to provide a dead air space between the two and thus provide an effective insulation between the 80 furnace and the boiler room.

Referring now to the drawings for a better understanding of my invention, I show in Figs. 1 and 2 a furnace wall embodying a plurality of spaced, aligned tubes 10—10. 85 The tubes 10—10 may have water circulating therein, and, for that purpose, are shown as being connected to a suitable header 11. At 12 is shown a fragmentary portion of the fuel bed which comes in contact with the 90 lower portion of the furnace wall. It is to be understood that the furnace wall, as illustrated, may be any one of the boundary walls of a boiler furnace.

Cooperating with the spaced, aligned tubes 95 10—10 are my improved wall elements 13—13 and 14—14. The wall elements 14—14 are adapted to be installed, as will more clearly appear hereinafter, where the wall is in contact with the fuel bed, while the elements 13—13 are applied above the fuel bed of the furnace.

Referring now particularly to Figs. 2, 3 and 4, each of the wall elements 14—14 comprises a flat panel portion 16 and a hook-like portion 17, said hook-like portion 17 conforming in inner contour to the outer contour of the tubes 10—10. The panel portion 16 of each of these elements is adapted to form, in cooperation with a similar ele-

110

ment, a substantially continuous flat wall. The hook-like portion 17 extends practically the entire length of the element and extends substantially half way round its associated tube 10. The hook-like portion 17 of an adjacent cooperating wall element 14 also extends substantially half way round the tube 10 so that the tube is almost completely embraced by two associated wall elements. 5 The construction just described prevents abrasion of the tubes 10—10 and their consequent wearing away by action of the fuel adjacent thereto should it be desired to apply the wall elements 14—14 with the hook-like portions 17—17 towards the inside of the furnace. In order to hold the elements 14—14 in place, I provide, in each end of each of the portions 17 of the elements, a slot 18 adapted to receive a key member 19, so that when the elements 14—14 are assembled in place with their associated tubes 10—10, and the keys 19—19 inserted, the whole forms a unitary structure. In order to prevent leakage between the wall elements 20 I may provide grooves 21—21 in the edges of the elements in which suitable packing 22 may be inserted.

In applying the elements 14—14 they may be disposed so that either the flat portions 30 16—16 are on the outside of the furnace or on the inside thereof. It more often is the case that the structure surrounding the lower part of a furnace may prevent the application of the elements adjacent thereto from 35 the exterior of the furnace and I accordingly show them in Fig. 1 with the flat portions 16—16 on the inside of the wall. This method of application further affords greater protection to the tubes from the abrasive effects of the fuel bed. This particular form 40 of wall element may be removed from either side of the furnace wall.

It will be apparent that, with the keys 19—19 removed, an element may be readily 45 removed from an associated tube by pulling it outwardly therefrom toward the panel portion 16. It may also be removed from the opposite side of the furnace, as shown in Fig. 4, by sliding upwardly or downwardly an associated element 14 and pulling it 50 between the tubes toward the hook-like portion 17.

With the form of wall element just described, where the structure expands and 55 contracts due to temperature changes in the furnace, the clearance between the elements allows for such expansion and contraction while the packings 22—22 prevent leakage into or out of the furnace.

60 Referring now particularly to Figs. 1, 5 and 6, the wall elements 13—13 each comprise a flat panel portion 20 and a pair of hook-portions 25 and 23. The hook portions 25 and 23 conform in inner contour 65 to the tubes 10—10 and extend part way

round an associated tube 10 a sufficient distance to insure a unitary structure of the wall when assembled.

Formed on the flat surface 20 of each of the elements 13 adjacent one side thereof is 70 a lug 24 which is adapted to cooperate with a similar lug 24 of an adjacent member 13 in order to hold the wall elements 13—13 in place. When assembled, a resilient U-shaped member 26 is applied astride a pair of lugs 75 24—24. In this way, the adjacent elements are held in contact; and, at the same time, the resiliency of the U-shaped member 26 allows the members 13—13 to yield upon expansion or contraction of said elements or 80 of the tubes 10—10, or both. The U-shaped member 24 performs yet another function in holding the wall elements 13—13 tightly against the tubes 10—10, bearing as it does, against the two lugs 24—24, the coating 85 edges of the elements 13—13 act as a fulcrum, thereby permitting the U-shaped member 24 to pull the hook portions tightly inward of the row of tubes 10—10 and hold the wall elements 13—13 firmly in place. 90

With this form of construction, there is also provided grooves 21'—21' along the edges of adjacent elements, whereby a suitable packing 22' may be inserted to prevent leakage in or out of the furnace. 95

Should it be desired to remove any one of the elements 13—13 while the furnace is in service, it is only necessary to remove the U-shaped member 26, whereupon either of the adjacent members 13—13, normally held 100 in place thereby, may be pulled out of place in the direction of the flat surface 20, or from the interior of the furnace.

Should it be desired to remove one of the members 14, which is located below a member 13, the U-shaped member 26 and the member 13 above the member 14 is removed, whereupon the key 19, holding the members 14—14 in place, may be removed and the member 14 removed from the furnace wall 110 as previously described in connection with Fig. 4.

With the form of wall elements 13—13, it will be obvious that I provide the greatest possible amount of heat transfer between the furnace and the tubes 10—10. At the same time absorption of heat by the water in the tubes 10—10 prevents the elements from becoming overheated and deteriorating. I have determined by actual test that this form of furnace wall is particularly free from damage due to overheating and that it may well last as long as any other part of the boiler. To those skilled in the art this advantage will be particularly appreciated because of the necessity of frequent renewal of a purely refractory furnace wall such as is commonly known. 120

Referring now to Fig. 7, I show a furnace wall 30 made up of units such as described 130

- with reference to the previous figures of the drawings. It will be apparent that, with such a wall, some arrangement should be made to prevent undue radiation of heat 5 into the boiler room. This may be accomplished in various ways, but preferably I provide an outer wall comprising a plurality of sections 31—31. The sections 31—31 may be wholly or partly composed of a suitable 10 heat-insulating material so as to prevent undue radiation of heat therethrough. In order to hold the sections in place, I provide, a suitable number of T beams 32—32 and bolt the sections 31—31 thereto as by bolts 33—33. 15 The outer wall is spaced from the inner wall 30 a sufficient distance to provide a dead air space of substantial width thus providing a considerable degree of heat insulation. The outer wall, with its sheets 31—31 of heat-insulating material, further impedes the radiation of heat, and the combined structure thus provides an ideal furnace wall installation. 20
- From the foregoing, it will be apparent 25 that I have devised an improved water-cooled furnace wall embodying wall elements easily installed and replaced, together with an improved furnace wall installation capable of preventing undue heat radiation exteriorly 30 of the furnace.
- While I have shown my invention in several forms it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims. 35
- What I claim is:
1. In a furnace wall, a pair of spaced tubes, a pair of elements forming a closed wall on one side of the tubes, means carried by each of the elements and extending part way around a cooperating tube for supporting said element and arranged to permit the ready removal of said element from the wall and resilient means permitting relative expansion between the elements for connecting the elements together. 45
  2. A furnace wall comprising a series of spaced tubes for the circulation of a cooling medium, individual wall elements arranged along one side of the tubes, supporting means carried by each of the wall elements and extending part way around the cooperating tubes, and resilient retaining means joining the wall elements together and permitting relative movement upon expansion and contraction. 55
  3. In a furnace, a series of aligned and spaced water circulating tube members along a boundary of the furnace, a plurality of cooperating pairs of wall elements dis- 60
- posed along the side of the tube members remote from the furnace and cooperating therewith to form a section of a furnace wall, hook-like members carried by the wall elements and extending in engaging relation part way around the cooperating tube members and permitting insertion or removal of the individual wall elements from the outer side of said furnace wall, cooperating juxtaposed lugs formed on each pair of wall elements on the outer side of the furnace wall, 70 and a resilient U-shaped member joining the lugs together. 75
4. In a furnace, a pair of spaced tube members, a pair of wall elements disposed on one side of the tube members and cooperating with said tube members to form a furnace wall, a hook-like member carried by each of the wall members and extending inwardly of the furnace and part way around a cooperating tube, lugs formed on the wall members exteriorly of the furnace, and resilient means for joining the lugs together. 80
5. In a furnace, a pair of spaced tube members, a pair of wall elements disposed on one side of the tube members and cooperating with said tube members to form a furnace wall, a hook-like member carried by each of the wall elements and extending part way around a cooperating tube, a lug formed on each of the wall elements on the side thereof most remote from the furnace, and means joining the lugs together to form a unitary structure. 90
6. In a furnace, a pair of spaced tube members, a pair of wall elements disposed on one side of the tube members and cooperating with said tube members to form a furnace wall, a hook-like member carried by each of the wall elements and extending inwardly of the furnace part way around a cooperating tube, a lug formed on each of the wall elements on the side thereof most remote from the furnace, and resilient means permitting relative expansion and contraction between the wall elements for joining the lugs together and forming a unitary structure. 100
7. In a furnace, a series of aligned and spaced tube members, series of pairs of wall elements disposed along one side of the tube members and cooperating therewith to form a section of a furnace wall, a hook-like member formed on each of the wall elements and extending inwardly of the furnace in engaging relation part way around a cooperating tube member, lugs formed on the wall elements on the side thereof most remote from the furnace, and resilient means cooperating with lugs of each pair of elements for holding the latter in place. 115
- In testimony whereof, I have hereunto subscribed my name this 13th day of May, 1926.
- ROBERT A. FORESMAN.
